U. G. FULLER.

TYPE WRITING MACHINE.

APPLICATION FILED APR. 24, 1908.

921,606.

Patented May 11, 1909.

UNITED STATES PATENT OFFICE.

ULYSSES G. FULLER, OF HARTFORD, CONNECTICUT, ASSIGNOR TO UNDERWOOD TYPEWRITER COMPANY, OF NEW YORK, N. Y., A CORPORATION OF NEW JERSEY.

TYPE-WRITING MACHINE.

No. 921,606.

Specification of Letters Patent.

Patented May 11, 1909.

Application filed April 24, 1908. Serial No. 428,908.

To all whom it may concern:

Be it known that I, ULYSSES G. FULLER, a citizen of the United States, residing in Hartford, in the county of Hartford and State of Connecticut, have invented certain new and useful Improvements in Type-Writing Machines, of which the following is a specification.

This invention relates to paper feeding devices of typewriting machines, and is in the nature of an improvement upon the mechanism disclosed in Patent No. 889,855 to J. C. McLaughlin, in which the platen is swung backwardly and forwardly by a crank, the first movement to bring the platen to position to receive a bill, and the second movement to bring the bill to the printing point; said application relating particularly to means for securing blank spaces between the carbon entries of successive bills on a carbon sheet which is retained in the machine. In said application, a crank is shown mounted on the platen frame, but is normally out of engagement with the platen, a single swinging movement of the crank serving to rotate the platen. The crank is mounted loosely upon the platen axle, and a pawl or dog is pivoted upon the crank in position to engage a notched or toothed wheel, the latter being fixed to the platen; a spring normally holding the pawl out of engagement with the notched wheel. A single movement of the crank throws the pawl into engagement with the notched wheel, such engagement being mechanically maintained until the crank is swung back to normal position, whereupon the spring throws the pawl or dog out of engagement with the toothed wheel, and also serves to hold the crank in its normal position. In said application, the crank-operating dog is caused to skip one or more notches or teeth of the wheel during the initial portion of the initial stroke of the crank (or other finger piece) and then to engage said wheel to turn it around, so that the platen is turned backwardly during the remainder of said stroke of the crank. The engagement of the dog with said wheel is also maintained during the entire return movement of the crank to normal position, so that the forward rotation of the platen effected by said wheel is greater than the backward rotation thereof. Thus the platen is caused to turn backwardly a relatively short distance to receive a bill, and then forwardly a relatively long distance to bring the bill to printing position; and in this manner a space is left between the carbon records on the long record sheet, which is retained in the machine during the writing of successive bills, as understood in this art. That is to say, the record sheet is turned back with the platen through a certain arc to the point where a new bill is introduced, and is then turned forward with the platen through a greater arc, so that the record of the new bill is separated by a space on the record sheet from the record of the immediately preceding bill.

The object of the present invention is to simplify, and improve the latch or trip which causes the dog to skip the teeth of the notched wheel to effect the spacing between the successive bills on the carbon sheet. To this end, I provide a pivoted arm or latch having at one end a lateral tongue or projection which forms a substantial continuation of the circular guide that engages the dog pin to maintain the dog in engagement with the notched wheel. I provide upon the stop disk a spring to lift the dog pin up past the end of said tongue, so that the pin may travel behind or above said tongue to hold the dog away from the wheel, during the initial portion of the initial stroke of the crank. The pin engages a bevel formed upon the stationary stop disk, and is caused thereby to throw the dog into engagement with the notched wheel, such engagement being maintained by means of the circular guiding wall usually provided upon the stop disk or rack. Upon said latch back of the tongue, I form an abutment which is engaged by the dog pin at the return stroke of the crank to arrest the same. I also provide a yielding finger to engage the pin to hold the crank against accidental movement during the working of the typewriting machine. Other features and advantages will hereinafter appear.

In the accompanying drawings, Figure 1 is a plan of the platen and platen frame, partly broken away, of an Underwood front strike typewriting machine embodying my improvements, the crank being shown in a normal position of disuse. Figs. 2 to 6 are diagrams showing different stages in the movements of the crank and its appurtenances. Fig. 7 shows the latch. Fig. 8 is a perspective of the upper portion of the stop.

disk and the latch pivoted thereon. Fig. 9 is an elevation showing the crank in normal position. Fig. 10 shows the same swung forwardly and connected to the notched wheel. Fig. 11 shows the crank arrested by the adjustable stop at the completion of the forward stroke of the crank. Fig. 12 is a sectional front elevation taken along the platen axle. Fig. 13 shows the crank, and Fig. 14 an edge view of the dog and parts rigid therewith. Fig. 15 is a perspective of part of the dog.

The usual cylindrical platen 1 of an Underwood typewriting machine is fixed upon an axle 2 journaled in the ends 3, of a platen frame, the end of the axle projecting through the platen frame end and having a finger-wheel 6 thereon by means of which the platen may be rotated forwardly or backwardly to an unlimited extent. The platen is also provided with the usual line-spacing devices, of which a toothed line-space wheel 7 and a yielding detent 8 therefor are seen at Fig. 1. Said line-space wheel is advanced intermittently by a pawl 9 and lever 9^a. Upon the end of the platen axle is secured a hub 10 of a wheel 14 having teeth or notches 15 agreeing in number with the teeth on the line-space wheel 7.

The wheel 14 is rotatable by means of a slide or dog 16 having a tooth 17 to engage the teeth 15 of the wheel, but normally disengaged therefrom, as at Figs. 1, 2 and 9, to permit independent rotation of the wheel 14 and the platen 1. Said dog or part 16 is attached by a screw 18 to a plate 18^a on the opposite face of a crank 19, the latter having a longitudinal guiding slot 20, to receive a block 18^b which forms part of the plate 18^a. The crank has a hub 19^a to fit upon a sleeve 19^b secured upon the platen axle 2.

In order to effect backward rotation of the platen, the crank is swung from its normal rear position, Figs. 1, 2, 9, forwardly as at Fig. 3, this initial portion of the movement of the crank causing the tooth 17 to pass idly by two or more teeth of the wheel 14. The dog carries a pin 21 which during such initial portion of the crank movement passes idly along over the tongue 22 formed upon an arm or latch 23, which is pivoted at 24 upon a fixed disk 25, the latter mounted loosely upon the sleeve 19^b, but secured against rotation by means of a link 26 connecting it to a stud 27 upon the platen frame.

When the pin 21 reaches the end of the tongue 22, Fig. 3, it engages a bevel 28 formed on said disk, and during further movement of the crank is cammed by said bevel toward the platen axle 2, Fig. 4, to cause the dog tooth 17 to engage one of the teeth of the wheel 14, Figs. 4 and 10. The crank is swung forwardly still more until it

is arrested by engagement with a stop 29, the latter mounted on a swinging arm 30 and having a pin 31 to engage any of a series of stop holes 32 in the disk 25. After the engagement of the dog 17 with the wheel 14, such engagement is preserved by reason of the engagement with the pin 21 with a circular guiding wall 33 formed upon the disk around the wheel, said wall acting to confine the dog, so that it cannot escape from wheel, and hence the platen must rotate backwardly and forwardly with the crank 19, which is provided with a handle 34.

Upon the return stroke of the crank the pin 21 passes from the circular guiding wall 33 onto the under side of the tongue 22, and rides along said tongue which forms substantially a continuation of said circular guiding wall, and hence the tooth 17 of the dog is maintained in engagement with the wheel 14, and continues to turn the latter during the entire return stroke of the crank 19, so that the distance through which the platen turns forward after the fresh bill is introduced is greater than the distance that it was turned back to receive said bill, thus introducing a blank space between the entries on the carbon sheet which remains in the machine during the withdrawal of the old bill and the insertion of the new one.

Upon the completion of the return stroke of the crank a spring 35, provided upon the stop disk, engages the pin 21, and throws it up past the end of the tongue 22, which is nearest the pivot 24 of the latch; the pin 21 engaging an abutment 36 formed upon said latch to arrest the crank. A spring finger 37 secured upon the edge of the stop disk 25 normally engages the pin 21, Fig. 2, to hold the crank 19 yieldingly against accidental movement during the operation of the typewriting machine; and said finger 37 also forms a support for the pin 21 during the movement of the latter from Fig. 2 to Fig. 3 to enable said pin to act upon the tongue 22 to swing the arm 23 slightly inward, if desired, to conduce to ease of action of the device. After the pin 21 passes around the tongue, the spring 35 bearing against the arm 23 returns the latter to normal position, Fig. 5. The operator simply grasps the handle 34, and pulls the crank forward as far as it will go, and then after introducing a new bill pushes the crank back to its starting point, whereupon the first line of writing may be begun upon the new bill without attention from the operator to the matter of properly separating the records on the record sheet.

Having thus described my invention, I claim:

1. In a typewriting machine, the combination with a revoluble platen and a notched wheel connected thereto, of a crank mounted to swing about the axis of said notched

wheel, a dog mounted upon said crank for independent movement to engage said notched wheel, but normally disengaged from the wheel, a pin upon said dog, a guide 5 to engage said pin to retain the dog in engagement with said notched wheel, a pivoted arm or latch having at one end a lateral tongue, said tongue terminating between the ends of the pivoted arm or latch, and forming 10 a substantial continuation of said guide, and means to lift the pin up past the end of said tongue, so that the pin may travel behind or above said tongue to hold the dog away from the wheel during the initial portion 15 of the initial stroke of the crank, a device being provided adjacent to said tongue to be engaged by said pin during the initial stroke of the crank, to enable said pin to force said tongue aside and cause the dog 20 tooth to engage a notch of the wheel.

2. In a typewriting machine, the combination with a revoluble platen and a notched wheel connected thereto, of a crank mounted to swing about the axis of said notched 25 wheel, a dog mounted upon said crank for independent movement to engage said notched wheel, but normally disengaged from the wheel, a projecting pin upon said dog, a circular guiding wall to engage said 30 pin to retain the dog in engagement with said notched wheel, a pivoted yielding arm or latch having at one end a lateral tongue, said tongue forming a substantial continuation 35 of said guiding wall, and terminating between the ends of the pivoted arm or latch, a spring being provided to press the pin up past the end of said tongue, so that the pin may travel behind or above said tongue to hold the dog away from the 40 wheel during the initial portion of the initial stroke of the crank, said wall being provided with a beveled end adjacent to said tongue, to be engaged by said pin during the initial stroke of the crank, and to enable 45 said pin to force said tongue aside, and to cause the dog tooth to engage a notch of the wheel.

3. In a typewriting machine, the combination with a revoluble platen and a notched 50 wheel connected thereto, of a crank mounted to swing about the axis of said notched wheel, a dog mounted upon said crank for independent movement to engage said notched wheel, but normally disengaged from the 55 wheel, a projecting pin upon said dog, a circular guiding wall to engage said pin to retain the dog in engagement with said notched wheel, a pivoted yielding arm or latch having at one end a lateral tongue, 60 said tongue forming a substantial continuation of said guiding wall, and terminating between the ends of the pivoted arm or latch, a spring being provided to press the pin up past the end of said tongue, so that 65 the pin may travel behind or above said

tongue to hold the dog away from the wheel during the initial portion of the initial stroke of the crank, said wall being provided with a beveled end adjacent to said tongue, to be engaged by said pin during 70 the initial stroke of the crank, and to enable said pin to force said tongue aside, and to cause the dog tooth to engage a notch of the wheel, the arm or latch being provided with a stop to engage said pin to limit the return 75 movement of the crank.

4. In a typewriting machine, the combination with a revoluble platen and a notched wheel connected thereto, of a crank mounted to swing about the axis of 'said notched wheel, a dog mounted upon said crank for independent movement to engage said notched wheel, but normally disengaged from the wheel, a pin upon said dog, a guide 80 to engage said pin to retain the dog in engagement with said notched wheel, a pivoted arm or latch having at one end a lateral tongue, said tongue terminating between the ends of the pivoted arm or latch, and forming 85 a substantial continuation of said guide, means to lift the pin up past the end of said tongue, so that the pin may travel behind or above said tongue to hold the dog away from the wheel during the initial portion of the initial stroke of the crank, a device being 90 provided adjacent to said tongue to be engaged by said pin during the initial stroke of the crank, to enable said pin to force said tongue aside and cause the dog tooth to engage a notch of the wheel, and a stop adjacent to the end of said tongue, to limit the 95 return movement of said crank.

5. In a typewriting machine, the combination with a revoluble platen and a notched wheel connected thereto, of a crank mounted 105 to swing about the axis of said notched wheel, a dog mounted upon said crank for independent movement to engage said notched wheel, but normally disengaged from the wheel, a pin upon said dog, a circular 110 guiding wall to engage said pin to retain the dog in engagement with said notched wheel, a pivoted arm or latch having at one end a lateral tongue, said tongue terminating between the ends of the pivoted 115 arm or latch, and forming a substantial continuation of said guiding wall, a spring finger at the end of said tongue to press the pin up past said end, so that the pin may travel behind or above said tongue during 120 the initial portion of the initial stroke of the crank, said wall being formed with a beveled end adjacent to said tongue to be engaged by said pin during the initial stroke of the crank, to enable said pin to force said tongue 125 aside, and cause the dog tooth to engage a notch of the wheel, and said spring finger bearing against said arm or latch, to restore said tongue to normal position.

6. In a typewriting machine, the combina- 130

tion with a revoluble platen and a notched wheel connected thereto, of a crank mounted to swing about the axis of said notched wheel, a dog mounted upon said crank for independent movement to engage said notched wheel, but normally disengaged from the wheel, a pin upon said dog, a circular guiding wall to engage said pin to retain the dog in engagement with said notched wheel, a pivoted arm or latch having at one end a lateral tongue, said tongue terminating between the ends of the pivoted arm or latch, and forming a substantial continuation of said guiding wall, a spring finger at the end of said tongue to press the pin up past said end, so that the pin may travel behind or above said tongue during the initial portion of the initial stroke of the crank, said wall being formed with a beveled end adjacent to said tongue to be engaged by said pin during the initial stroke of the crank, and to enable said pin to force said tongue aside and cause the dog tooth to engage a notch of the wheel, and a spring finger bearing against said arm or latch, to restore said tongue to normal position; a stop being formed upon said arm or latch adjacent to said spring finger, to arrest said crank upon its return movement.

7. In a typewriting machine, the combination with a revoluble platen and a notched wheel connected thereto, of a crank mounted to swing about the axis of said notched wheel, a dog mounted upon said crank for independent movement to engage said notched wheel, but normally disengaged from the wheel, a pin upon said dog, a circular guiding wall to engage said pin to retain the dog in engagement with said notched wheel, a pivoted arm or latch having a lateral tongue, said tongue forming a substantial continuation of said guiding wall, means to carry the pin up past the end of said tongue, so that the pin may

travel behind or above said tongue during the initial portion of the initial stroke of the crank, said wall being formed with a beveled end adjacent to said tongue to be engaged by said pin during the initial stroke of the crank, and to enable said pin to force said tongue aside and cause the dog tooth to engage a notch of the wheel, and a spring finger bearing against said pin to prevent vibration of the crank when in normal position.

8. In a typewriting machine, the combination with a revoluble platen and a notched wheel connected thereto, of a crank mounted to swing about the axis of said notched wheel, a dog mounted upon said crank for independent movement to engage said notched wheel, but normally disengaged from the wheel, a pin upon said dog, a circular guiding wall to engage said pin to retain the dog in engagement with said notched wheel, a pivoted arm or latch having a lateral tongue, said tongue forming a substantial continuation of said guiding wall, means to carry the pin up past the end of said tongue, so that the pin may travel behind or above said tongue during the initial portion of the initial stroke of the crank, said wall being formed with a beveled end adjacent to said tongue to be engaged by said pin during the initial stroke of the crank, and to enable said pin to force said tongue aside and cause the dog tooth to engage a notch of the wheel, and a spring finger bearing against said pin to prevent vibration of the crank when in normal position; said spring finger extending along over said tongue to form a bearing or guide for said pin during a portion of its stroke.

ULYSSES G. FULLER.
